UNITED STATES PATENT OFFICE.

CECIL M. GRIFFIN, OF NEWBURGH, NEW YORK.

TUBE-CLEANING TOOL.

1,280,443.

Specification of Letters Patent.

Patented Oct. 1, 1918.

Application filed February 20, 1918. Serial No. 218,206.

To all whom it may concern:

Be it known that I, CECIL M. GRIFFIN, a citizen of the United States, and a resident of Newburgh, in the county of Orange and State of New York, have invented a new and useful Improvement in Tube-Cleaning Tools; and I do hereby declare the following to be a full, clear, and exact description thereof.

10 This invention relates to cleaning tools, and more particularly to cleaning tools for cleaning tubes of condensers and the like, and has for its principal object the provision of such a cleaner that will have a floating 15 adjustable action, so that it will pass easily over irregularities in the surface of the tube and still have a stiff gripping or cutting action upon the interior surface of the tubes to clean or scrape out any scale or other matter 20 which may be fastened to such interior surface.

Another object of my invention is to provide a cheap, simple and efficient tool of this class, which will be durable and which can 25 be easily applied in the tubes to be cleaned, and which will clean the tubes completely and uniformly, and in a rapid and convenient manner.

To these ends my invention consists, generally stated, of a rod or piston member having a helical scraper plate secured thereto in such a manner as to permit a floating action, as hereinafter more specifically set forth and described and pointed out in the claim.

35 In the drawings:—

Figure 1 is a top plan view of my scraper shown in a sectioned tube;

Fig. 2 is a side elevation of the same with the tube in cross section;

40 Fig. 3 is a view on the line 3—3 of Fig. 2; and

Fig. 4 is a rear end view of the device within a tube.

Like symbols of reference herein indicate 45 like parts throughout the several figures of the drawings.

As illustrated in the drawings A represents my improved cleaning tool, which is provided with a central bar or shank member 2, having a piston or head 3 at one end of the same, terminating in an inclined boss 7.

Extending around the bar 2 is a resilient 50 scraper blade 1, which is in the form of a coiled spring and bent to such shape for providing helix or spiral portions 5 around such

shank. The scraper member 1 when bent to form the helix portions 5, I prefer to form a little more than one convolution around the bar 2. 60

The cleaner or scraper is operated on and secured to the bar 2 by the portion 8, which is loosely mounted on the shank of the headed pin or rivet 4, which in turn is rigidly secured adjacent the forward end of such 65 bar. The front end of the scraper member 1 is free of the bar to allow for free expansion or contraction of such member.

The free end 6 of the spiral or helix members 5 are adjacent the head 3, and such 70 spiral or helix portions are larger than the tube B in which they are adapted to be inserted for the purpose hereinafter described, with such diameter depending upon the tension desired for operating in such tube. Of 75 course it will be understood that there are various sizes of tubes and that various sizes of cleaners will be used depending on the size of the tube to be cleaned.

The cross sections of the scraper or blade 80 1 decrease rearwardly toward its free ends so that the tension will be uniform throughout the length of the scraper 1.

The scraper blade 1 is so shaped that its cutting edge or the forward edge only comes 85 in contact with the inner surface of the tube being cleaned since a clearance is formed back of the cutting edge by beveling the blade 1.

When it is desired to place the tool A 90 within the tube B, it is simply pushed in front end first, the helix portions 5 of the scraper 1 being compressed and diametrically expanded until they conform to the size of the tube, so that such coils will be 95 sprung against the inner surface of such tube and bear against the same. After the tool A is thus in position at one end of the tube B, and it is desired to clean the interior surface of such tube, water under a 100 high pressure, through a nozzle (not shown) is passed into such tube to push said cleaner through. By forcing the tool A through the tube B, it will be observed that the coils or helical portions of the scraper 1 will 105 scrape or loosen all the dirt, scale or other foreign matter from the interior surface of the tube.

It will thus be seen that my improved tube 110 cleaning tool is capable of being easily and cheaply manufactured and is ready for instant use when required. The tools will ad-

just themselves to conform to the size of the tube and are capable of being carried along with the other tools, and will not require any adjustment to use the same, while practical experience with the same has demonstrated that tubes can be cleaned cheaply and quickly, and with a great amount of saving in time and labor.

While I have shown and described one specific form of my invention in the accompanying drawings and specification, it will be apparent that various sizes and designs may be made by one skilled in the art without departing from the spirit of my invention as defined in the appended claim.

What I claim is:

A tool adapted to be inserted in tubes or

20 pipes for cleaning the same, comprising a central bar having an enlarged head on its forward end, a headed pin secured in the forward end of said bar, and a single scraper blade having its forward end loosely mounted for sliding movement upon the shank of said pin, said blade being bent around said bar more than once to form rearwardly extending helical portions of a greater diameter than the diameter of the said enlarged head.

In testimony whereof I, the said CECIL M. GRIFFIN have hereunto set my hand.

CECIL M. GRIFFIN.
